UNITED STATES PATENT OFFICE.

HENRY F. KRÜGER, OF NEW KENSINGTON, PENNSYLVANIA.

ENVELOP.

No. 922,600.

Specification of Letters Patent.

Patented May 25, 1909.

Application filed July 30, 1908. Serial No. 446,141.

To all whom it may concern:

Be it known that I, HENRY F. KRÜGER, a citizen of the United States, residing at New Kensington, in the county of Westmoreland and State of Pennsylvania, have invented 5 certain new and useful Improvements in Envelops, of which the following is a specification, reference being had to the accompanying drawings.

10 This invention relates to improvements in envelopes and similar containers and more particularly to those which have their sealing flaps protected so that they cannot be opened without detection.

15 The object of the invention is to provide a simple and practical safety envelop which may be produced at a comparatively small cost, will be convenient to use and will be sure to show evidences of a fraudulent attempt at opening.

20 With the above and other objects in view, the invention consists of the novel features of construction and the combination and arrangement of parts hereinafter fully described and claimed, and illustrated in the accompanying drawings, in which—

25 Figure 1 is a plan view of a blank from which the envelop is made; Fig. 2 is a view of the envelop made up and ready to receive its contents; Fig. 3 is a rear view of the envelop closed and sealed; and Fig. 4 is a vertical section taken on the plane indicated by the line 4—4 in Fig. 3.

30 The envelop comprises a front or body portion 1, two side or end flaps 2 and top and bottom flaps 3, 4. The side or end flaps 2 are substantially triangular in shape but have at their apexes squared portions or tongues 2^a adapted to overlap each other when said flaps 2 are folded inwardly and to form a 35 guard or shield for the contents of the envelop, as presently explained. The top flap 3 is substantially triangular in shape and at its apex is formed a large tongue 5 and a smaller tongue 6, the latter being at the center of the outer portion of the tongue 5. A coating of gum or the like 7 is placed on the inner face of the flap 3, and also upon the tongues 5, 6; and if desired, gum may also be placed upon the outer faces of the tongue 6 and a portion of the tongue 5. The bottom flap 4 is also substantially triangular in shape but has its apex rounded and formed adjacent to said apex is a longitudinally curved 45 or arc-shaped opening or slot 8 to receive the tongue 5. The bottom flap 4 is provided

50 on its inner face around its edge with a coating of gum or the like 9 which is adapted to unite it to the outer faces of the side or end flaps 2 after the latter have been folded over upon the front 1. The shape of the tongues or extensions 2^a on the flaps 2 and the arrangement of the curved slot 8 is such that when the envelop is made up ready for use, as shown in Fig. 2, the tongues or extensions 2^a are disposed beneath the slot 8 and the central portion of the flap 4 to form a guard to protect the contents C of the envelop. It will be noted that the width of the upper flap 3 and its tongue 5 is such that 55 when the latter is inserted in the slot 8 it will just reach to the bottom edges of the extensions or tongues 2^a on the flaps 2 and therefore be prevented from coming in contact with and adhering to the contents of the 60 envelop but that the small safety sealing tongue 6 will project beyond the bottom edges of the tongues or extensions 2^a and will adhere to the contents so that the latter 65 cannot be removed without destroying said 70 tongue 6. In making up the envelop, the side or end flaps 2 are folded over upon the front 1 and the bottom flap 4 is then folded up, and glued to the flaps 2, as shown in Fig. 75 2 of the drawings.

80 In using the envelop the contents C is placed therein and the gum 7 on the flap 3 is moistened and the latter is then folded down and its tongues 6, 5 passed through the slot 8. The tongue 5 will adhere to the 85 extensions or tongues 2^a on the end flaps 2 to more effectively unite the latter, and at the same time said tongues or extensions 2^a will prevent the tongue 5 from contacting with the contents C of the envelop. The 90 small tongue 6, however, will adhere to the letter or other contents of the envelop and will very likely be torn when the flap 3 is surreptitiously opened; and it will therefore be practically impossible for the contents to 95 be replaced and the flap 3 resealed without the envelop showing evidences of having been tampered with. The tongue 5 being sealed beneath the flap 4 cannot be moistened and opened without detection as may 100 be the sealing tongue of an ordinary envelop.

105 From the foregoing it will be seen that the improved envelop is very similar to an ordinary envelop and may be as quickly cut, gummed and made up as the latter. The 110 curvature of the slot 8 permits the tongue 5 to be readily inserted in the same and the

engagement of said tongue 5 with the extensions 2^a on the flaps 2 causes the latter to be more effectively united and hence renders the envelop stronger. When the safety 5 feature is not desired the flap 3 may be sealed on the outside the same as the sealing flap of an ordinary envelop. The simplicity of the envelop renders it inexpensive to produce and easy to seal and at the same time 10 it is practically impossible to obtain access to the contents of the envelop without detection.

Having thus described the invention what is claimed is:

15 A safety envelop comprising an oblong rectangular front, tapered side flaps folded over upon the back of the front and provided with squared overlapping free ends, the latter having their lower edges straight 20 and parallel with the upper and lower edges of the front and spaced from said lower edge to expose the letter sheet within the sealed envelop, a triangular bottom flap folded over upon said side flaps and gummed at its 25 side edges to the latter, said bottom flap being provided at its vertex with a slot, a

triangular top flap adapted to be folded down upon the side and bottom flaps and gummed at its edges for attachment thereto, a main tongue upon the apex of the top 30 flap adapted to be passed through said slot between the bottom flap and squared ends 35 of the side flaps and gummed on its rear face for attachment to the outer faces of the latter, the tip of said tongue being adapted when inserted to align with the said straight lower edges of the ends of the side flaps, and a reduced supplemental tongue or tab extending from the tip of the main tongue in axial alignment with the center of said slot 40 and also gummed on its rear face, said supplemental tongue being adapted to be attached to the letter sheet within the sealed envelop, below the straight lower edges of the ends of the side flaps, substantially as 45 described.

In testimony whereof I hereunto affix my signature in the presence of two witnesses.

HENRY F. KRÜGER.
